UNITED STATES PATENT OFFICE.

JOHN BRANDWOOD, OF BIRKDALE, SOUTHPORT, ENGLAND.

FLUID TREATMENT OF ARTIFICIAL SILK YARNS.

Application filed August 29, 1927, Serial No. 216,300, and in Great Britain September 2, 1926.

The dyeing and other analogous liquid treatment—herein deemed to be included in the expression “dyeing” where the context admits—of artificial silk yarns in skeins present problems which do not present themselves in the treatment of staple fibers, e. g. cotton. The nature of the artificial silk in the wet state causes considerable waste if the material is carelessly handled and it is a desideratum therefore that it should in that state be subjected to as little handling as possible by the operatives in a mill. In usual practice, the skeins after dyeing have to be removed from their holders and are then placed in perforated boxes or other receptacles and subjected, for the removal of superfluous moisture, to whizzing in the usual hydro-extractor apparatus, this involving the bunching up of the skeins, with waste of material and moreover of time employed in the operation of removal and whizzing in this condition. Further, the affinity of liquor for the artificial silk differs from that of cottons and other fibres, and care has to be exercised in the liquor treatment e. g. dyeing, if the yarns are to be evenly penetrated.

The objects of the present invention are two-fold, viz: to ensure that yarns in skein or loop form need to be handled in their wet state as they come from a dye bath by providing for removal of the superfluous moisture from the skeins without changing their skein form, and to dye and treat large quantities of the yarns in a rapid and efficient manner, with a saving of labour and time and also a considerable saving in waste.

According to the invention I immerse the skeins in a dye bath and give them the desired movement or movements reversing such movement or movements if desired in the said bath for the purpose of dyeing and then remove the skeins and the volume of bath liquor out of contact, then giving the skeins a rotary motion at a high speed around their own centres so that the superfluous moisture is removed therefrom by centrifugal force. Any movement may be given to the skeins in the dye bath which movement will serve for the effective dyeing of the skeins but I prefer to give the said skeins movement in two directions, one in the direction of the yarn length of the skein and the other in a direction substantially perpendicular to such yarn lengths, these two movements being imparted to the skeins simultaneously.

The invention with a very suitable apparatus for carrying it into effect, will now be described with reference to the accompanying drawings wherein:

Figures 1 and 2 are respectively a plan—broken—and a side elevation of a treatment tank to illustrate means for treating yarn skeins mounted on a plurality of holders simultaneously.

Figure 3 is a fragmentary section of a treatment tank with a yarn holder in position therein to show the means for mounting and driving a holder within the tank, Figure 4 being a section of Figure 3. These figures show also the detailed construction of a preferred type of skein holder. In Figures 1 and 2 a tank 5 of convenient size to take a plurality of skein holders at a single charge is shown, this tank being of ordinary form and construction and as known in the dyeing and other treatment of textiles, having a storage tank communicating therewith and a pump which may charge the said tank with the liquor and empty it as desired, or by suitable manipulation of valves, circulate the liquor through the said tank during the treatment of the yarns. At each position in the tank for such a holder is screwed or bolted to one tank wall 6 a V 85 guide 7 of metal, the lower end of the guide being formed as a bearing 8 for the end of such a holder and in which bearing such end may rotate freely. On the opposite wall 9 of the tank 5 at each holder position is a similar V guide 10 with a similar bearing 11. Each skein holder can thus be safely and certainly lowered into its bearings 8 and 11 in the tank without chance of error or the necessity of fumbling in the liquor bath on the part of the operatives.

At each holder position in the tank 5 is fitted a driving stub shaft 12 which passes through the wall 6 of the tank and to ensure liquor tightness, through a gland 13. Each 100 such shaft 12 has keyed on the inner end thereof, that is within the tank 5, a spur wheel 14 and on the outer ends of these stub shafts 12 are keyed the rope pulleys 15 grooved for the reception of an endless drying rope 16 which passes over and under the successive rope pulleys 15 in series—see Figure 2—and around guide pulleys 17, and a tensioning pulley 18. The tensioning pulley 18 is borne on slideable bearings 19 in slotted side brackets 20 which bearings are vertically adjustable by threaded spindle 21

and the handwheel 22 as known in connection with such tensioning pulleys. Pedestal bearings, of known form and construction, are provided at 23 for the stub shafts 12.

One of the shafts 12—see right hand of Figure 1—is prolonged at 24, and passes through a pedestal bearing 25 the extreme end of this shaft prolongation having keyed thereon the bevel gear wheel 26 which is in constant mesh with two further bevel gear wheels 27 and 28 rotatably mounted on the shaft 29 which is supported in bearings 30. Upon the shaft 29 and midway between the two gear wheels 27 and 28 is mounted by a sliding key and keyway a clutch member 31 each face of which is formed as a dog clutch to engage with corresponding clutch members 32 and 33 on the bevel gear wheels 27 and 28. Upon the end of the shaft 29 is keyed a further bevel gear wheel 34 in mesh with a further bevel gear wheel 35 keyed on a shaft 36 on which is also keyed the worm gear wheel of a reduction gear 37 the worm drum of which is fitted on a driving shaft 38 of a motor. To give the skein holders within the tank the necessary movements therefore the clutch member 31 is engaged with one of the bevel gear wheels 27, 28, and from motor shaft 38 and the transmission gearing rotation is imparted to shaft 29 and the shaft prolongation 24 and by the interconnecting rope drive to all the holders simultaneously. To reverse this motion the clutch member 31 is engaged with the other bevel gear wheel, and to stop such rotation the clutch member 31 is placed in its non-operative position, which it occupies in Figure 1.

A further clutch 39 slidable upon the motor shaft 38—left hand of Figure 1—is adapted to engage with a bevel gear wheel 40 rotatably mounted on the said motor shaft 38 and meshing with the further bevel gear wheel 41 which is keyed on a prolongation 42 of the end shaft 12, this prolongation being borne in a pedestal bearing 43. The shaft 38 therefore through this transmission gearing may drive all the shafts 12 simultaneously but at a higher speed than that required for liquor treatment. The ratio of these two speeds may be any desirable.

By this arrangement as described, each stub shaft 12 will receive rotation in one direction or the other as desired from the gearing at the right hand side of Figure 1 and will also receive, when desired, rotation in one direction from the gearing at the left of Figure 1, but at a higher speed; and a method of communicating the rotation of these shafts 12 to the skein holders to give the looped skeins the movements desired will now be described, reference being had 65 to Figure 1 and also to Figures 3 and 4.

Referring first to Figures 3 and 4, which show a skein holder which is of suitable dimensions to fit in the bearings 8 and 11 of the tank 5 of Figure 1 when its ends are dropped in the V guides 7 and 10 of such tank. End brackets 44 and 45 are connected by the longitudinal shaft 46 which is secured in the brackets by means of a nut 47 and the shaft 48 also serves to secure the brackets together. This latter shaft 48 however passes through slots 49 in the brackets and one end enters a bearing 50 which is slidable in one of the slots 49 in brackets 45. The other end of the shaft passes through the slot 49 in bracket 44. The bearing 50 is flanged at 51 to keep it in sliding position and the milled nut 52 serves to secure the shaft bearing in any adjusted position in the slot 49 of bracket 45. To each bracket 45 is secured the end shafts 53 and 54 which rest in the bearings 8 and 11 of the V guides 7 and 10 in the tank. 70 75 80 85 90 95

On each of the shafts 46 and 48 is rotatably mounted a pair of flanges 55 and 56 which are connected by six tubes 57 placed angularly at regular intervals around the said shaft. Each aggregation of flanges 55 and 56 and the tubes 57 forms an arbor and when in operation skeins of yarn are mounted on the said arbors to fill the space 95 between the flanges 55 and 56.

Compounded with the flange 55 of each arbor by means of a collar 58 which is rotatable in the bracket 44 is the spur pinion 59, and each of these pinions 59 meshes with a central spur gear wheel 60 which is loose on the end shaft 53 of the holder. The spur gear wheel 60 bears a boss 61 having a radial metal peg 62 which is adapted to be engaged by the end of a pivoted lever 63, 105 which is orificed for the purpose. On this end shaft 53, again, is a spur pinion 64 which when the holder is in position in the treatment tank, drops upon and meshes with the spur gear wheel 14 of one of the stub shafts 12. The holder is shown in Figures 3 and 4 as being in position in the bearings 8 and 11 of the V guides 7 and 10 already described with reference to Figure 1, but to a larger scale than in that figure. The use 110 of the spur gear wheel 60 and of its restraining lever 63 will be fully explained hereinafter when the operation of the machine is described.

To collapse the holder for the purpose of 120 passing a charge of yarn skeins thereon, the nut 52 is slackened and the spur gear wheel 61, which as stated is loose on the shaft 53, is slidden towards the spur pinion 64. The shaft 48 with the flanges and tubes forming 125 the arbor can then be moved inwardly so that the charge of skeins may be easily mounted on the holder.

It will be seen that when the holder is charged the shaft 48 and its borne arbor can 130

be moved back to the position of Figures 3 and 4, the spur gear wheel 61 moved back into position to mesh with the spur pinions 59 and the nut 52 again screwed up.

5 It will be understood that this charging operation takes place before the holder is placed in its bearings 8 and 11 in the tank. A suitable frame or table may be provided to receive the holder during the said operation.

10 The dimensions of the holder are such that a heavy charge of skeins may be placed thereon if desired, and the extreme width or transverse dimension of the holder when 15 fully extended is such that the skeins are held thereon with a certain degree of slackness which will avoid damage to them but will prevent their interference one with the other as they pass through the volume of 20 liquor in the bath.

25 In the construction shown, the collar 55 of the lower arbor in the figure rests against the lower end of the slot 49 in bracket 44, and the spur gear wheel 61 meshing with the spur pinions 59 maintains it in that position without special securing means on that side of the holder, but as will be understood securing nuts may be arranged to maintain the shaft 48 in position when the 30 said shaft is again adjusted outwardly when the holder is fully charged with skeins.

The operation is as follows:—

A skein holder is placed upon a suitable table or frame and one end bracket 45 removed. The spur gear wheel 61 which is loose on the centre shaft 53 is moved back and the arbor shaft 48 with its arbor is moved radially inwardly of the holder so that skeins may be easily slipped over the 40 two arbors, the holder being thus charged with the desired number of skeins between the flanges 55 and 56. These latter are of a dimension which will allow of the skeins slipping over them easily. The holder being 45 charged the bracket is again screwed into position and the said holder lifted by means of a winch or other device—or by hand if the apparatus is not a large one—and allowed to drop into its bearings 8 and 11 in 50 the V guides 7 and 10. When in this position the spur pinion 64 on the central shaft 53 of the holder meshes with spur gear wheel 14 on the stub shaft 12 of the holder position. The lever 63 is then moved and 55 engages by its orifice with the peg 62 on the boss 11 of the spur pinion 60 thus rendering the latter stationary. All the holders of the apparatus are thus charged and positioned in the tank 5, and the clutch 31 of 60 Figure 1 being engaged with the bevel gear wheel 27 and the motor started the holders all rotate around their own central axes. At the same time, due to the meshing of spur pinions 59 of the arbors of each holder with 65 the central pinion 60, the arbors each have

rotation around their own axes, the skeins thus having the two movements desired; one in the direction of their yarn length and the other substantially perpendicular to such yarn length owing to the bodily movement 70 of the skeins around the central axes of the holder.

When the treatment has been continued for the desired time the clutch 31 is moved over and engaged with the bevel gear wheel 75 28 of the gearing of Figure 1 and the two movements of the skeins are thus reversed, this alternate change of direction taking place as often as desired.

The liquor treatment being completed, the 80 clutch 31 is moved to its free position between the bevel gear wheels 27 and 28 and all movement of the skeins stops, the tank 5, is then emptied sufficiently to free the skeins of all contact with the liquor volume 85 of the bath and the levers 63 are then moved to disengage them from the spur wheels 60 of the skein holders. The clutch 39—left hand side of Figure 1—is engaged with the bevel gear wheel 40 to clutch the latter and 90 motor shaft 38 together. Rotation of the skein holders through the gearing operation the stub shafts 12 and the meshed gear wheels and pinions 14 and 64 now commences, but at a higher speed than that 95 afforded by the gearing to the right hand side of Figure 1, this higher speed of rotation of the holders being sufficient to throw off the superfluous moisture from the skeins—which are now in atmosphere—by 100 centrifugal force. The skeins in this operation are not moved in the direction of their yarn length, as the spur gear wheels 61 of all the skein holders are again loose and are simply idle wheels, imparting no drive to the 105 arbors. The holders are then removed from the tank and an end bracket 45 of each being again removed and the holder collapsed by inward movement of the arbor shaft 48, the skeins are removed to be replaced by a fresh 110 charge.

By totally immersing the skeins in the liquor whilst leaving to the said skeins just sufficient slackness on their arbors to prevent them making contact with each other 115 during their movements, a floating effect is produced which keeps them in their respective positions on the arbors. Further, the use of an aggregation of tubes as an arbor allows of the access of the treatment liquor to all parts of the skein at one time so that the movements given to the skeins allow of their being treated evenly with the liquor. Further, the whole construction of the apparatus permits of a very large quantity of 120 skeins being treated at one time.

Any part of the apparatus may be of non-corrodible metal or alloy or be coated or lined with such a metal or alloy or with other material such as ebonite which will 125 130

withstand corrosion effects of any liquor employed.

Any means of driving the stub shafts may be adopted as an alternative to the means described and shown and the mechanical details of the skein holder may also be varied.

I claim:—

1. For the dyeing and subsequent drying by centrifugal force of artificial silk threads in looped skein form, a holder to receive the skeins, movable skein bearing surfaces in the holder, means for rotating the holder around its own axis and for moving the said skein bearing surfaces simultaneously, and means for causing the cessation of movement of the skein bearing surfaces whilst rotating the holder around its own axis.

2. For the dyeing and subsequent drying by centrifugal force of artificial silk threads in looped skein form, a holder to receive the skeins, movable skein bearing surfaces on the holder, connected means for rotating the holder around its own axis and for moving the said skein bearing surfaces simultaneously, means for causing the cessation of movement of the skein bearing surfaces whilst rotating the holder around its own axis, a central shaft in the holder, a treatment tank, a driving shaft in the treatment tank, means for positioning and bearing the holder in the treatment tank, means for rotating the driving shaft at two different speeds, and driving means between the said driving shaft and the holder centre shaft.

3. For the dyeing and subsequent drying by centrifugal force of artificial silk threads in looped skein form, a holder for the skeins, rotatable arbors in the holder which arbors form yarn bearing surfaces, a spur pinion on each arbor, a central shaft in the holder, a spur gear wheel rotatably and slidably mounted on the central shaft and meshable with the spur pinions, and a fixed lever engaging with the spur gear wheel to convert it into a fixed gear wheel and disengaging therefrom to convert it into an idle gear wheel, for the purpose set forth.

4. For the dyeing and subsequent drying by centrifugal force of artificial silk threads in looped skein form, a holder for the skeins, rotatable arbors in the holder which arbors form yarn bearing surfaces, a spur pinion on each arbor, a central shaft in the holder, a spur gear wheel rotatably and slidably

mounted on the central shaft and meshable 55 with the spur pinions, and a fixed lever engaging with the spur gear wheel to convert it into a fixed gear wheel and disengaging therefrom to convert it into an idle gear wheel, a treatment tank, a driving shaft in 60 the treatment tank, means for positioning and bearing the holder within the treatment tank, means for rotating the driving shaft at two different speeds, and driving means between the said driving shaft and the holder centre shaft.

5. For the dyeing and subsequent drying by centrifugal force of artificial silk threads in looped skein form, rotatable arbors in the holder which arbors form skein bearing surfaces, a spur pinion on each arbor, a central shaft in the holder, a spur gear wheel rotatably and slidably mounted on the central shaft and meshable with the spur pinions, a fixed lever engaging with the spur gear 75 wheel to convert it into a fixed gear wheel and disengaging therefrom to convert it into an idle gear wheel, a treatment tank, V guides within the tank, bearings at the bottom of such V guides, a driving shaft with 80 fixed spur wheel within the tank, and a spur wheel on the central shaft of the skein holder, these spur wheels meshing when the holder is positioned within the tank by the V guides, and means for rotating the driving 85 shaft at two different speeds.

6. For the dyeing and subsequent drying by centrifugal force of artificial silk threads in looped skein form, a holder to receive the skeins, movable skein bearing surfaces on 90 the holder, means for rotating the holder around its own axis and for moving the skein bearing surfaces simultaneously, means for causing the cessation of movement of the skein bearing surfaces whilst rotating the holder around its own axis, a treatment tank, a driving shaft in the treatment tank, V guides within the tank, bearings at the bottom of such V guides, a spur gear wheel on the driving shaft within the tank, a spur 95 gear wheel on the central shaft of the holder, these spur gear wheels meshing when the holder is positioned by the V guides, and means for rotating the driving shaft at two 100 different speeds.

In testimony whereof I have hereunto set my hand.

JOHN BRANDWOOD.
